JENS MORTENSEN, OF FREEPORT, AND LEOPOLD TROPP, OF BROOKLYN, NEW YORK,
ASSIGNORS, BY MESNE ASSIGNMENTS, TO STEINER SALES COMPANY, A CORPORA-
TION OF UTAH.

PAWL MECHANISM.

Application filed January 26, 1926. Serial No. 83,779.

This invention relates to a new and improved feed and control mechanism for dispensing a roll of toweling so that successive portions thereof can be exposed for use outside of a cabinet in which the roll of toweling is enclosed.

One of the objects of this invention is to provide a simple, convenient and noiseless mechanism for preventing the backward feed 10 of the mechanism.

Another object of this invention is to devise a simple and compact form of structure in which a shield separates the clean portion or run of the toweling from the soiled 15 portion thereof.

Other objects of this invention will be set forth in the following description and drawings which illustrate a preferred embodiment of this invention, it being understood 20 that the above general statement is intended merely to generally explain the same and not to limit it in any manner.

Fig. 1 is a front elevation.

Fig. 2 is a section on the line 2—2 of 25 Fig. 1.

Fig. 3 shows the parts illustrated in Fig. 2, but in different relative positions.

Fig. 4 is a section on the line 4—4 of 30 Fig. 1.

Fig. 5 is a detail view illustrating the control device for preventing the backward movement of the mechanism.

Fig. 6 is a perspective view of one of the parts of the mechanism.

The cabinet 2, which can be provided with 35 any suitable door, is provided with inner side plates 5 upon which the various parts of the mechanism are mounted. The roll of clean toweling T is placed upon the

bottom of the cabinet 2, as shown, for example, in Fig. 4. Bars 18 and 19 are mounted upon pivoted carriers P and 62 which are respectively connected to their respective side plates 5 by means of pins 16 and 63.

The clean toweling is led over and around 40 the inner bar 18 which is preferably non-revoluble (although it might be revolubly mounted), then around the lower roller R' 45

which is mounted upon the shaft 14, then around the outer bar 19 which is also preferably non-revolubly mounted (although it might be revolubly mounted), then through an opening in the front of the bottom of the cabinet, then through a second opening in the rear of the cabinet (a loop 50 of sufficient length being exposed for use below the bottom of the cabinet), then above a shield S pivotally mounted on a bar 62' connected to the end plates 5, and then around bar or roller 6^x and the upper roller 60 R mounted on the shaft 9, and then around a take-up roller 6 to form a roll T'. When the device is first set into operation, a few turns of the end of the toweling are passed 55 around the roller 6 which slides and can turn in vertical slots provided for this purpose in the side plates 5. The weight of the take-up roller 6 is sufficient to cause it to be turned by the movement of the upper roller R so that the take-up mechanism is 60 continuously operated when the front of the toweling is pulled downwardly. The rollers R and R' are preferably provided with corrugated rubber facings so as to secure a 65 sufficient grip upon the toweling passed 70 around it.

In order to prevent more than a predetermined length of the toweling from being 75 pulled out of the cabinet by means of a single pull, the control mechanism shown in Figs. 2 and 3 is utilized. The lower shaft 14 is provided with a star wheel 12 and this 80 engages with the pins 11 on a cogwheel 8 which is mounted upon a shaft 9 of the upper rollers R and R' to be simultaneously 85 upper roller R. This causes the rollers R and R' to be simultaneously actuated. The carrier P is provided with a pawl 22 pivoted thereto by means of pin 21 and the movement of the pawl 22 is limited by the fixed pins 34 and 34' connected to the carrier P. The outer end of the pawl 22 normally rests upon the lower pin 34, as shown in Fig. 2. The star wheel 12 is 90 provided with a stop 23 fixed thereto by 95 rivets or the like.

When the outer portion of the exposed loop of the toweling is pulled downwardly, this causes the carrier P to be moved inwardly from the normal position shown in Fig. 2 (in which position it is kept by the force of gravity) into the position shown in Fig. 3, so that the inner end of the pawl 22 will be projected in the path of movement of the stop 23. When the stop 23 contacts 10 with the inner end of the pawl 22, it turns the said pawl around its pivot pin 21 until the upper recessed portion of the pawl 22 engages with the upper pin 34', thus locking the parts against movement. When, however, the pull on the front portion of the 15 exposed loop of toweling is released, the force of gravity acts to move the carriers P and 62 back into the position shown in Fig. 2. When the pawl 22 is moved away 20 from the position shown in Fig. 3, the inner end thereof is moved upwardly because the outer end of the said pawl 22 then drops upon the lower supporting pin 34, so that it is impossible for the stop 23 to again engage the inner nose of the pawl 22, until the 25 lower roller R' together with the connected star wheel 12 are moved for substantially another complete revolution.

As shown in Figs. 4 and 6, the inner arm 30 of the support 62 is sufficiently long and heavy to cause it to normally assume the position shown in Fig. 4 in which the said inner arm rests upon a projecting end of the shaft 14. In this position the pawl 22 is moved into what may be called the inoperative position, shown in Fig. 2.

In order to prevent a reverse motion of the feed mechanism, a catch 50 is pivotally mounted upon a pin 55 connected to one 40 of the side plates 5. A wire spring 52 has its inner end bent around the upper shaft 9 so that there is a frictional engagement between this loop portion of the spring 52 and the shaft 9. The spring 52 has a lateral 45 portion 53 which may also be in close contact with the inner surface of the cogwheel 8 so as to provide additional frictional engagement. The spring 52 is then bent away from the cogwheel 8, as shown in Fig. 1, and it is then bent upwardly and a loop 54 is then formed which loosely engages the catch 50. A fixed pin 51 connected to one of the end 50 plates 5 limits the upper movement of the catch 50. When the parts are actuated in the correct direction, then the star wheel 12 is actuated in the counter-clockwise direction and the cogwheel 8 is actuated in the clockwise direction, if it is assumed that the observer is at the right-hand side of the 55 parts illustrated in Fig. 1. The frictional engagement between the wire spring 52 and the shaft 9 (and also possibly with the inner face of the cogwheel 8) causes the upper end or loop 54 of the wire spring 52 to be 60 raised so as to raise the catch 50 into the

position substantially shown in Figs. 2 and 3, for example. The pin 51 limits the upper movement of the catch 50. It will be noted that when the wheel 8 is revolved that the spring 52 is not substantially distorted and 70 that the lateral branch 53 is not wound up on the shaft 9. The spring 52 is only distorted or bent to an extent sufficient to overcome the weight of the catch 50. The angular portion of the spring between the 75 loop thereof on the shaft 9, and the loop 54, is of an angular shape, and the outer branch of this is raised in a direction substantially perpendicular to the longitudinal axis of the catch 50. 80

In this position the parts can be freely actuated without the objectionable rattling noises which would be caused if the ordinary pawl and ratchet wheel mechanism were used. If, however, the back portion of the 85 exposed loop is pulled downwardly, then the frictional engagement between the spring 52 and the shaft 9 (and possibly with the inner face of the cogwheel 8) causes the loop 54 to be moved downwardly, thus moving the catch 50 into the position shown in 90 Fig. 5, so that it engages one of the pins 11 of the cogwheel 8. An efficient and noiseless control is thus provided.

The plates 5 may be connected adjacent 95 their upper ends by the brace bar 60. The control mechanism thus described noiselessly checks the feed of the towel save in the proper direction, prevents more than a pre-determined amount of the toweling from being withdrawn from the cabinet at a single 100 pull, and efficiently separates the clean portion of the toweling from the soiled portion thereof. When the bar 18 is moved to its inner position, it does not necessarily press the toweling against the surface of the lower roller R'. Experience has shown that this is unnecessary, because the arrangement of the bars 18 and 19 produces such a large 105 area of contact that the toweling does not slip upon the lower roller R' when said lower roller is locked against movement. 110

We have shown a preferred embodiment 115 of our invention, but it is clear that numerous changes and omissions could be made without departing from its spirit.

We claim:

1. In a feed and control mechanism for dispensing a roll of toweling, a wheel 120 mounted on a shaft and connected to the feed mechanism and having spaced pins projecting from one of the lateral faces thereof, a pivoted catch having an end face adapted to engage the said pins and to prevent the revolution of said wheel in one direction, the pivot of the said catch being external to the said wheel and a spring having a loop on the shaft of the said wheel and in frictional engagement with the said 125 shaft, the said spring being connected to the 130

said catch and being adapted to move it the outer arm of the said angular portion into the operative or into the inoperative being directly connected to the said catch. position, dependent upon the direction of In testimony whereof we affix our signatures.

- 5 2. A device according to claim 1 in which the said spring has an angular portion intermediate the said loop and the said catch,

JENS MORTENSEN.
LEOPOLD TROPP.
